UNITED STATES PATENT OFFICE.

ROBERT BEARDSLEY, OF CHICAGO, ILLINOIS.

ARTICLE-FORMING DEVICE.

Application filed April 4, 1927. Serial No. 180,925.

This invention relates to new and useful improvements in article forming devices which are particularly adapted for use in the manufacture of lamp shades.

5 One of the objects of my invention is the provision of a device of the kind described which is especially adapted for use in forming a seam in a lamp shade after the application of adhesive to a portion of the blank from 10 which the shade is formed.

A further object of my invention is the provision of a device of the kind described which includes a form upon which lamp shades or other articles of paper or similar 15 material are placed when it is desired to glue parts thereof together, means being included in the construction of the device whereby to guide the parts to be glued and to retain them in proper position during the operation. The 20 device further includes means for subjecting the parts to heat and pressure to facilitate the drying of the adhesive.

Many other objects and advantages of the construction herein shown and described will 25 be obvious to those skilled in the art from the disclosure herein given.

To this end my invention consists in the novel construction, arrangement and combination of parts herein shown and described, 30 and more particularly pointed out in the claims.

In the drawings, wherein like reference characters indicate like or corresponding parts:

35 Fig. 1 is a top plan view of a device constructed in accordance with my invention;

Fig. 2 is a side elevation;

Fig. 3 is a vertical sectional view on the line 3—3 of Fig. 1;

40 Fig. 4 is a detail bottom plan view of one of the presser bars;

Fig. 5 is a plan view of the other presser bar;

Fig. 6 is a transverse section taken on the 45 line 6—6 of Fig. 3;

Fig. 7 is a plan view of a blank which is used in the construction of lamp shades of paper or similar material; and

50 Fig. 8 is a substantially cone-shaped lamp shade formed from the blank illustrated in Fig. 7.

My improved device is particularly adapted for use in connection with the making of lamp shades constructed from parchmentized 55 paper or similar material, and has particular reference to the guiding and bringing to-

gether of the parts to which adhesive has been applied in order to retain these parts in proper position during the drying of the adhesive. As shown in Fig. 7, the blank A in 60 the construction of a lamp shade has adhesive applied to one of its marginal edges as shown at B and the edge C is lapped over the adhesive on B and the two edges retained in this position until the adhesive is dried, which 65 will form the shade illustrated in Fig. 8, and in order to facilitate the drying of the adhesive, it is preferred to apply heat to the parts so that the shades may be manufactured rapidly in commercial quantities. 70

One embodiment of the invention is attached to a workbench or table 1 having supporting legs 2, the attaching means including a base plate 3 secured to the table by means of bolts 4, or the equivalent. 75

The device comprises two parallel bars 5 and 6. The bar 5 forms the supporting bar and is attached at its inner end to the base plate 3 by means of the screw bolts 7. The outer end of the bar 5 projects a suitable distance beyond the outer edge of the base plate 3, and attached thereto is a substantially cone-shaped form 8, the outer end of which is flush with the outer end of the bar 5 and is secured to the bar by means of the screw bolts 9. 80

The uppermost bar 6 is preferably mounted for movement toward and away from the bar 5 and lies parallel therewith, its ends being flush with the ends of the bar 5. The bar 6 is provided adjacent its inner end, with laterally projecting studs 10 which are slidably mounted within slots 11 formed in the guide plates 12 secured to the bar adjacent its inner end. In order to further guide the movement of the bar 6 and retain the same parallel with the bar 5, guiding plates 13 are arranged at a point adjacent the inner end of the form 8 with their upper ends projecting beyond the upper face of the bar 6 as shown in Fig. 2. 90

In order to impart movement to the bar 6 to move the same toward and away from the bar 5, I provide an oval-shaped cam 14 rotatably mounted between the upper ends of the plates 13 and actuated by means of an arm 15, one end of which is attached to the 100 cam supporting shaft 16, while the other end is provided with a plurality of openings 17. Movement may be imparted to the arm 15 through the medium of a link 18, the upper end of which is adjustably connected, by 105 means of a bolt 19, to the outer end of the arm 15, while the lower end pivotally connects 110

with a treadle bar 20. From this it will be apparent that upon downward movement of the treadle bar 20 the cam 14 will be rocked upon its pivot 16, forcing the bar 6 downwardly toward the bar 5.

The two bars 5 and 6 are normally maintained in spaced relation by means of a coil spring 21, the ends of which are mounted within suitable pivots arranged in the opposed faces of the bars 5 and 6, the tension of the spring normally urging the bars apart as shown in Fig. 3. It will be apparent that when the oval-shaped cam 14 is in a locking position and the treadle 20 released, the tension of the spring 21 is preferably such that it will not force the two bars apart, and in order to impart a slight movement to the cam 14 to assist in the moving of the bars away from each other, a lever 22 is attached 20 to the pivot 16 for imparting slight movement to the pivot when it is desired to release the cam.

The opposed faces of the bars 5 and 6 are each provided with rows of spring pressed pins 23 and 23', the pins in the row of one bar being arranged alternate with the row of pins on the other bar, as illustrated in Fig. 2, so as to evenly distribute the pressure of these pins against the edges of an article placed between the two bars. Thus, when the two edges B and C of the blank 8 are positioned between the bars, the spring pressed pins 23 will have a tendency to properly position the edges whereby to cause the adhesive 30 on edge B to adhere to edge C. In order that the end portions of the edges B and C will be uniform, guide pins 24 and 25 are arranged at the outer ends of the bars 5 and 6 so that the end portions of the blank may be positioned against these pins as illustrated 40 in Fig. 6.

In placing the edges of the blank A in position between the bars 5 and 6, it will be noted that one of the edges is arranged in abutting relation with the row of pins 23 which are arranged upon one side of the longitudinal center of the bar 5, while the other edge of the blank is arranged in abutting relation with the pins 23' which are arranged upon the side of the longitudinal center of the bar 6 directly opposite the position of the pins 23.

The above is clearly illustrated in Fig. 6, and it will be noted that when the edges are 55 properly positioned against the pins 23 and 23', they will be clearly overlapped so that the adhesive applied to the edge B will be engaged by the edge C. From this it will be apparent that when the bar 6 is moved downward toward the bar 5, the overlapped edges will be properly positioned before being glued together and will be retained in this position until the adhesive has thoroughly dried.

60 65 In order to facilitate drying of the adhesive

applied to the edge B and which adheres to the edge C, a burner 26 is arranged within the form 8 and disposed directly beneath the bar 5 so that the heat from the burner will be applied directly to the parts being glued together. 70

It will be apparent from the foregoing that in using my improved device the form A has the adhesive applied at B, the edges then placed between the bars 5 as shown in Fig. 6, 75 with the end portions abutting the pins 24 and 25, and the overlapped edges abutting the pins 23 and 23' so that when the shade is completed, the ends thereof will be even as shown in Fig. 8. After the edges have been made 80 uniform, the foot treadle 20 is pressed downwardly, causing the cam 14 to turn and force the bar 6 toward the bar 5, clamping the edges together. The shade is allowed to remain in this position a short duration of time 85 and upon release of the same, if the cam 14 fails to move upon release of the treadle 20, the lever 23 is actuated to cause the cam to be returned to an inoperative position as shown in Fig. 2 by means of the coil spring 21. 90

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. In a device of the character described and in combination, a stationary support, means resiliently mounted on said support for correctly positioning one edge of a blank, a movable presser bar, resiliently mounted 105 means for correctly positioning the other edge of the blank relative the first edge, and means for moving the movable presser bar toward the stationary support to bring the positioned edges into contacting relation. 110

2. In a device of the character described and in combination, a stationary support, a form carried by said support, means resiliently mounted on said support for correctly positioning one edge of a blank, a movable 115 presser bar, resiliently mounted means on the presser bar for correctly positioning the other edge of the blank relative the first edge, means for moving the movable presser bar toward the stationary support to bring the edges together, and means for supplying heat to the edges. 120

3. In a device of the character described and in combination, a stationary support, means resiliently mounted on said support 125 for correctly positioning one edge of a blank, a movable presser bar, resiliently mounted means for correctly positioning the other edge of the blank relative the first edge, means carried by said support and bar for 130

aligning the ends of said edge portions, and means for moving the movable presser bar toward the stationary support.

4. In a device of the character described and in combination, a stationary support, means resiliently mounted on said support for correctly positioning one edge of a blank, a movable presser bar, resiliently mounted means for correctly positioning the other edge of the blank relative the first edge, means carried by said support and bar for aligning the ends of said edge portions, and means for supplying heat to said edges.

5. In a device of the character described and in combination, normally spaced parallel members, means for correctly positioning the edges of a shade between said members with said edges in overlapped relation, and means for moving one of said members into clamping engagement with the overlapped edges.

6. In a device of the character described and in combination, normally spaced parallel members, means for correctly positioning the edges of a shade between said members with said edges in overlapped relation, and manually operated means for moving one of the members into clamping engagement with the edges.

30 7. In a device of the class described and in combination, normally spaced parallel clamping members, means normally urging one of said members away from the other and retaining said members in normally spaced 35 relation, means for guiding the edges of a lamp shade between said members, and means for clamping one of said members on to the

edges of the blank for retaining said edges against movement.

8. In a device of the character described and in combination, normally spaced parallel members, means for correctly positioning the edges of a shade between said members with said edges in overlapped relation, and a cam acting against one of said members for moving the same into clamping engagement with the overlapped edges and locking said members in clamped position.

9. In a device of the kind described and in combination, a support, means mounted on said support for positioning one edge of a blank, a presser bar, means mounted upon said presser bar for positioning a second edge of said blank relative to said first mentioned edge, and means for producing relative movement between said support and presser bar to bring the positioned edges into contacting relation.

10. In a device of the kind described and in combination, a stationary support, a form carried by said support, resiliently mounted pins on said support for positioning one edge of a blank, a movable presser bar, resiliently mounted pins on said presser bar for positioning a second edge of said blank relative to said first mentioned edge, cam means for moving the presser bar toward the stationary support to bring said edges of the blank together, and means for supplying heat to the edges.

In testimony whereof, I have hereunto signed my name.

ROBERT BEARDSLEY.
